UNITED STATES PATENT OFFICE.

JOHN A. MCANULTY, OF MINNEAPOLIS, MINNESOTA.

PITMAN.

SPECIFICATION forming part of Letters Patent No. 394,281, dated December 11, 1888.

Application filed March 26, 1888. Serial No. 268,548. (No model.)

To all whom it may concern:

Be it known that I, JOHN A. MCANULTY, a citizen of the United States, residing at Minneapolis, in the county of Hennepin and State 5 of Minnesota, have invented certain new and useful Improvements in Pitmen; and I do hereby declare the following to be a full, clear, and exact description of the invention, such as will enable others skilled in the art to which 10 it appertains to make and use the same.

My invention relates to pitmen for connecting cranks or eccentrics, either revolving or rocking, to parts of machinery which are designed to be reciprocated; and it consists in 15 the improved construction and arrangement or combination of parts of the pitman and its connections, which will be hereinafter fully disclosed in the description, drawings, and claims.

20 The objects of my invention are, first, to provide improved means for vibrating or reciprocating parts of machinery without the use of separate springs for supporting the same, and, second, to provide improved means 25 for attaching pitmen to eccentrics, eccentric-shafts, or crank-pins in such a manner that rattling and heating of boxes will be prevented and free play allowed to the part vibrated or reciprocated without binding or unequal wear upon said eccentrics, eccentric-shafts, or crank-pins.

30 In the accompanying drawings, forming part of this specification, wherein the same reference-numerals indicate the same or corresponding parts, Figure 1 represents a top plan view of my improved pitman connected to an eccentric-shaft and to a part of a machine adapted to be vibrated or reciprocated, and Fig. 2 a longitudinal section of the same 35 on line $x-x$ of Fig. 1.

40 In the drawings, the numeral 1 indicates the shaft, which is provided with a crank or an eccentric and a pitman attached thereto, only one of each being herein disclosed; but in practice two or more may be employed, as their construction will be the same.

45 2 represents the eccentric, which may be formed by reducing the shaft, as shown in the drawings, or by attaching an eccentric of larger radius than the shaft, or in any of the well-known ways of forming cranks or eccentrics.

The cylindrical box 3, as shown in section in Fig. 2, is formed in two parts and so fitted upon the eccentric as to permit the latter to move or revolve freely within it; also, the upper part thereof may be provided with an oil-cup, 4, adapted to receive and distribute a suitable lubricant to the eccentric and throughout the interior of the box. The two parts of the box have diametrically-opposite conical depressions 5 placed at an angle of 55 about forty-five degrees to the axial line of the pitman and the plane of the mechanism 60 to be reciprocated.

65 6 represents the pitman, which is formed at its inner end with a curved head, 7, which passes around more than half of the box, preferably beneath the same. A point or pivot, 8, is formed upon the inner side of this curved head and is so fitted into the depression 5 in the lower part of the box as to pivot freely therein laterally; also, the extreme end of this curved head is formed with a screw-threaded opening, 9, at a point diametrically 70 opposite the point or pivot 8. A set-screw, 9', which also acts as a pivot, passes through this opening and fits with its conical end in the depression 5 in the upper part of the box. A binding-nut, 10, firmly holds the set-screw in 75 its adjusted position. By tightening this set-screw a perfect adjustment of the two-part box to its crank or eccentric is effected and wear compensated for.

80 The outer end of the pitman or connecting-rod 6, which is attached to the part to be vibrated or reciprocated, is formed with a spiral or coiled spring, 11, which, being lengthwise compressible and expansible and laterally and vertically yielding or movable, serves to permit the part to which it is attached to move freely in all directions, and also serves to cushion the shock ordinarily incident to the reciprocating or vibrating frames employed in various kinds of machines—such as middlings-purifiers, feed-regulators, and grain-cleaners—especially in those machines in which the parts moved are rapidly reciprocated. This cushioning or avoidance of jar 85 is due to the resiliency of the metal forming 90 the spring portion of the pitmen, which enables me to dispense with the springs ordinarily employed for supporting shaking frames 95 in machines of the kind just named.

It will be obvious from the foregoing that the spring portion of the pitman in connection with the pivots, arranged at an angle to its axial line and forming a laterally-movable connection between the inner end of the same and the eccentric, will permit freedom of lateral movement of said pitman at both ends, and also allow the part being reciprocated to deviate from a line at right angles to the shaft; that all irregularities in the motion of said reciprocating or vibrating part will be taken up or compensated for; that uneven wear upon the eccentric and the two-part boxing due to heating from the binding or cramping and rapid movements of the parts, is entirely avoided, and, also, that rattling of the joints or couplings is prevented.

This construction of pitman is especially adapted to be used in machines of the character above referred to for the treatment of grain or its products in any form, since in that class of machines the principal parts not only require reciprocating or vibrating movement, but cushioning, as they are subjected to varying loads or pressures of stock; but, as is evident, my generally improved pitman, with its curved head pivoted to the crank-pin or eccentric at diametrically-opposite points, may be employed in any mechanism in which a pitman is required to permit of lateral or vertical play of the part to which it is attached.

I do not broadly claim a pitman having a coiled or spiral spring near its outer end, but only in combination or arrangement with the other parts and features herein specified in the claims; also, I do not claim the combination of a crank-pin and a pitman connected thereto by means of a ring and a box within said ring, which is pivoted upon two points which are coincident with the axis of said pitman, as this construction does not permit of the wide range and freedom of lateral movement of the outer end of the pitman that is incident to the laterally-movable pitman employed by me and provided with pivots arranged at an angle to the axial line of said pitman; also, I do not herein broadly claim this construction of laterally-movable pitman, as the same forms part of a similar in-

vention for which I have filed application for Letters Patent simultaneously herewith, Serial No. 268,547.

Having thus fully described the construction, arrangement, and operation of the several parts of my invention and also the advantages thereof, what I claim as new is—

1. The combination of an eccentric, a box mounted thereon, and a laterally-movable pitman provided with pivots at its inner end, arranged at an angle to its axial line, and provided near its outer end with a spring portion which is lengthwise compressible and expansible and laterally and vertically yielding or movable, substantially as and for the purpose described.

2. The combination of an eccentric, a box mounted thereon, and a laterally-movable pitman provided with pivots at its inner end, arranged at an angle to its axial line, and provided near its outer end with a coiled or spiral spring, substantially as and for the purpose described.

3. The combination, with a pitman formed with a curved head having diametrically-opposite pivotal points at its end and inner side, and with a coiled or spiral spring near its outer end, of an eccentric and a box mounted thereon and formed with diametrically-opposite depressions, in which said pivotal points rest, substantially as described.

4. The combination of a shaft provided with an eccentric, and a cylindrical box mounted thereon and provided with diametrically-opposite depressions in its sides, with a pitman having a spiral spring near its outer end and a curved head at its inner end, formed with a pivotal point on its inner side resting in one of said depressions, with a screw-threaded opening in its outer end and provided with a pointed set-screw having its end resting in the other depression, and a clamping-nut for holding said screw, substantially as described.

In testimony whereof I affix my signature in presence of two witnesses.

JOHN A. MCANULTY.
